UNITED STATES PATENT OFFICE

2,455,857

HOLDER

James E. Donaldson, Columbus, Ohio

Application November 13, 1945, Serial No. 627,977

12 Claims. (Cl. 211—89)

1

This invention relates to a holder; more specifically to a supporting device for suspending small articles of clothing.

After laundering small articles of clothing such as hosiery, etc. it is very desirable to have a readily accessible hanger bracket, or supporting device, from which the articles may be suspended for drying. Since such a supporting device is, of expediency, usually placed in one of the more accessible rooms of a home, it is extremely desirable in that it serve as a wall ornament when it is not in use.

An important object of this invention is to provide a readily accessible supporting device from which articles of clothing may be suspended after laundering.

Another important object is to provide a supporting device for freshly laundered articles, which can be placed in a non-use position, and which in said position, will have an ornamental effect.

Another important object is to provide a supporting device for articles, which device can be latched in a non-use position, in which it occupies but little space.

Further objects of this invention will become apparent from the disclosure described in the following specification and shown in the accompanying drawings in which:

Fig. 1 is a front elevational view of my improved supporting device positioned against a wall in a non-use position;

Fig. 2 is a sectional view taken along the line 2—2 of Fig. 1;

Fig. 3 is a sectional view, similar to Fig. 2, showing a supporting device in a position where it may be used to support articles of clothing or the like;

Fig. 4 is a detail view in perspective of the outer convex surface of a portion of the supporting device;

Fig. 5 is a detail view in perspective of the inner concave surface of the same portion of said supporting device; and

Fig. 6 is a detail view in perspective of a bracket member of said device.

A supporting device, generally indicated by the numeral 10, is positioned against a flat surface such as a wall 11, as best shown in Figs. 1 and 2. The supporting device 10 consists of a fan shaped member 12, having an inner concave surface 13, and an outer convex surface 14. Formed in said fan shaped member 12 are a plurality of arcuate finger portions 15 having rounded tips or end portions 16, said finger portions 15 having separations between them in the form of slots 15'. A pair of

2

spaced members 17 and 18 are formed in the bottom of said fan shaped member 12 and extend downwardly. A pair of bores 19 and 20 are positioned in opposite relationship within said spaced members 17 and 18, respectively. A boss 21, having an opening 22, is connected to one of the finger portions 15 within the concave surface 13.

As best shown in Figs. 1, 2, 3, and 6, a bracket member 23 is connected to the wall 11, by fasteners, such as screws 24. The bracket member 23 consists of a flat vertical portion 25 having a protruding portion 26 at the top thereof. The protruding portion 26 has an opening 27 through which is connected one end of a flexible sustaining element, such as a chain or cord 28. The other end of the flexible element 28 is fastened to the boss 21. The lower end of the bracket member 23 is formed with a cupped portion 29, and contains bores 30 and 31 spaced in opposite relationship to each other.

The lower end of the bracket member 23 is positioned between the spaced members 17 and 18 (see Fig. 1). Hinge pins 32, 32 are positioned within the bores 19, 20, 30, and 31 to permit hinged movement of said fan shaped member 12 with respect to said bracket member 23.

When not in use the fan shaped member 12 is positioned vertically against the wall 11 as best shown in Fig. 2. In this position the bracket member 23 is substantially enclosed and the boss 21 frictionally engages the protruding portion 26 of the bracket 23, thus securing said fan shaped member 12 in the vertical non-use position.

For suspending articles of clothing, such as a stocking, etc., indicated by the numeral 33 in Fig. 3, the fan shaped member 12 is rotated upon the hinge pins 32, until it is in a horizontal position substantially at a right angle to said bracket member 23. One of the finger portions 15, preferably the one centrally located in the fan shaped member 12, as best shown in Figs. 1 and 2, is provided at its end with a lip portion 34. This lip portion 34 permits the user to easily grip the fan shaped member for rotating it into the use position. The cupped portion 29 and the cord 28 retain the fan shaped member 12 in this use position. The ends of the fingers 15 are rounded so as to preclude damaging of the articles to be suspended between the slots 15'. The unique shape of the fan shaped member 12 is such as to fit snug against the wall 11 thereby keeping the supporting device 10 out of the way in its non-use position, and substantially enclosing said bracket portion 23 so as to expose a minimum amount of surface where dust may be collected.

It is to be understood that a preferred embodiment of the invention has been shown and described and that further modifications may be made that do not depart from the spirit of the invention, nor the scope thereof, as defined in the appended claims.

I claim:

1. A supporting device adapted to be positioned in a use and a non-use position, comprising a fan shaped member having an inner concave surface and an outer convex surface; a plurality of arcuate finger portions formed in said fan shaped member, said finger portions having rounded ends; a plurality of spaced members connected to the bottom portion of said fan shaped member; a boss upon said inner concave surface of said fan shaped member; a bracket member adapted to be enclosed within said concave surface of said fan shaped member, said bracket member having a bottom portion positioned between said spaced members; fastening means for connecting said bracket member to a substantially flat surface; a protruding member connected to the top portion of said bracket member and positioned to frictionally engage said boss to retain said fan shaped member in the non-use position; and means hingedly connecting said bracket member and said fan shaped member for permitting movement of said fan shaped member from a substantially vertical non-use position to a substantially horizontal use position.

2. A supporting device comprising a fan shaped member having an inner concave surface and an outer convex surface, a plurality of arcuate finger portions formed in said fan shaped member, a plurality of spaced members connected to the bottom of said fan shaped member, a boss mounted on said inner concave surface, a bracket member adapted to be enclosed within said inner concave surface, fastening means for connecting said bracket member to a substantially flat surface, a protruding member connected to the top portion of said bracket member, means hingedly connecting said bracket member to said spaced members, and a flexible element connected to said boss and said protruding member for limiting the hinged movement of said fan shaped member with respect to said bracket member.

3. A supporting device adapted to be positioned in a use and a non-use position comprising a fan shaped member having an inner concave surface and an outer convex surface, finger portions formed in said fan shaped member, a plurality of spaced members connected to said fan shaped member, a boss upon said fan shaped member, a bracket member having fastening means for mounting said bracket member, a protruding member connected to the top portion of said bracket member, means for hingedly connecting said bracket member to said spaced members, and means for retaining said fan shaped member in a horizontal use position; said boss and said protruding member being positioned to cooperate to frictionally retain said fan shaped member in a vertical non-use position.

4. A supporting device having in combination a shell shaped member provided with a concave surface and a convex surface, a plurality of fingers formed between said surfaces, dependent members connected to said fan shaped member, a boss connected to at least one of said finger portions, a bracket adapted to be enclosed within said fan shaped member, means for hingedly connecting said bracket to said dependent mem-

bers, means for vertically supporting said bracket, a cupped portion connected to said bracket and adapted to retain said fan shaped member substantially perpendicular to said bracket, and a protruding member on said bracket positioned to frictionally engage said boss and thereby retain said fan shaped member in vertical position.

5. A supporting device comprising a member having the shape of a concavo-convex seashell, a plurality of finger portions formed in said seashell shaped member, dependent members connected to said seashell shaped member, a boss connected to said seashell shaped member, a bracket smaller than said seashell shaped member, means for hingedly connecting said bracket to said dependent members, means for vertically supporting said bracket, means for retaining said seashell shaped member in horizontal position, and means adapted to engage said boss for retaining said seashell shaped member in vertical position substantially concealing said bracket.

6. A supporting device having in combination, a fan shaped member provided with a concave surface and a convex surface, a plurality of slots formed in said fan shaped member, a boss connected to said fan shaped member, a wall bracket, means for hingedly connecting said fan shaped member to said bracket, means for holding said fan shaped member substantially at a right angle to said bracket, and a latch connected to said bracket for frictionally engaging said boss to retain said fan shaped member adjacent said bracket, whereby said concave surface will substantially enclose said bracket.

7. A supporting device having in combination, a fan shaped member provided with a concave surface and a convex surface, said fan shaped member provided with slots forming fingers and being movable into a horizontal use position and a vertical non-use position; a bracket pivotally connected with said fan shaped member, means for fixing said bracket in vertical position, means associated with said bracket for holding said fan shaped member in the horizontal position, and latch means for holding said fan shaped member in the non-use position wherein said concave surface substantially encloses said bracket.

8. A supporting device adapted to be positioned in a horizontal use and a vertical non-use position, comprising a fan shaped member having an inner concave surface and an outer convex surface, a plurality of arcuate finger portions formed in said fan shaped member, a lip portion on one of said finger portions extending outwardly of said convex surface, a plurality of spaced members connected to the bottom portion of said fan shaped member; a boss on said inner concave surface of said fan shaped member, a bracket adapted to be enclosed within said concave surface of said fan shaped member with the lower portion of said bracket positioned between said spaced members, fastening means for connecting said bracket to a wall, a protruding member upon the top portion of said bracket positioned to frictionally engage said boss and thereby retain said fan shaped member in the non-use position, and means hingedly joining said bracket and said fan shaped member.

9. A garment supporting device having in combination a fan shaped member provided with a concave surface and a convex surface, a plurality of finger portions formed in said fan shaped member, a lip portion formed at the end of one of said finger portions for manually gripping said fan shaped member, dependent members

connected to said fan shaped member, a boss connected to said fan shaped member, a bracket smaller than said fan shaped member, means hingedly connecting said bracket to said dependent members, means for retaining said fan shaped member perpendicular to said bracket member, and means on said bracket for engaging said boss to retain said fan shaped member in vertical position, whereby said concave surface will substantially enclose said bracket.

10. A supporting device comprising a plurality of curved fingers arranged side by side to form a concavo-convex shell, means flexibly maintaining said fingers in said shell-like configuration, a wall bracket for said shell, a shaped projection on said bracket for receiving and supporting said means, means hingedly connecting said shell to said bracket, a supporting cord connected to said shell and said bracket for supporting the shell in horizontal position, and cooperating friction-lock means on said shell and on said bracket for maintaining said shell folded against said bracket.

11. A holder comprising a firm resilient unitary member having radiating, extending and gradually widening parts separated by narrow slots 25

radiating from a common center, articles being insertable into the slots, and the member provided with means for mounting it against a wall.

12. A holder of the class described, comprising 5 a unitary dished plate of resilient material having narrow slots separating yielding fingers wider at the outer ends and radiating from a common center, the dished side of the plate being uppermost to provide an open receptacle through which the 10 slots extend, and the member provided with means for mounting it against a wall.
